UNITED STATES PATENT OFFICE.

CONVERSE W. LLOYD, OF NEW YORK, N. Y., ASSIGNOR TO L. LYNN LLOYD, OF LINCOLN, NEBRASKA.

COLLAPSIBLE TOOTHBRUSH.

1,378,044.

Specification of Letters Patent. Patented May 17, 1921.

Application filed June 14, 1918. Serial No. 239,935.

To all whom it may concern:

Be it known that I, CONVERSE W. LLOYD, a citizen of the United States, and a resident of the city of New York, in the county of New York and State of New York, have invented certain new and useful Improvements in a Collapsible Toothbrush; and I do hereby declare that the following is a full, clear, and exact description of the same, reference 5 being had to the accompanying drawings, and to the numerals of reference marked thereon, which form a part of this specification.

This invention relates to an improved 15 form of a collapsible tooth brush wherein a tapered handle section of the brush head has the sides thereof slightly inclined toward one another from the outer surface of the handle section to the inner surface whereby 20 a wedge hinge construction is afforded when the handle is pivotally secured between flexible clamping jaws forming a part of the container handle of the device.

It is an object of this invention to construct a folding tooth brush having a wedge 25 construction at the hinged portion thereof adapted to hold the hinged sections of the tooth brush against folding when in open position for use.

Another object of the invention is the construction of a folding tooth brush provided 30 with a wedge hinge arrangement for holding the brush parts in extended position for use, one of said parts apertured to permit hanging up of the tooth brush when folded.

It is a further object of the invention to provide a self draining sanitary folding tooth brush having a frictional hinge construction between the brush head and the 40 container, said container being formed to permit the brush head when in closed position to seat against a stop and contact the end and side walls of the container and also affords openings between the brush head and 45 the inner walls of the container to permit ventilation and draining when the tooth brush is closed and hung up by means of an aperture formed in the container.

It is an important object of the invention 50 to construct a ventilated self-draining frictionally folding tooth brush provided with a means for hanging the same when in folded position.

Other and further important objects of the

invention will be apparent from the disclosure in the drawings and specification.

The invention (in a preferred form) is illustrated in the drawings and hereinafter more fully described.

On the drawings:

Figure 1 is a side elevation of a collapsible tooth brush in open position embodying the principles of my invention, with parts in section to show the construction.

Fig. 2 is a top plan view thereof.

Fig. 3 is a top plan view of the device in folded position.

Fig. 4 is a section on line 4-4 of Fig. 3, with parts shown in elevation.

Fig. 5 is an enlarged section taken on line 5-5 of Fig. 3.

Fig. 6 is an enlarged section on line 6-6 of Fig. 3.

Fig. 7 is an enlarged section taken on line 7-7 of Fig. 1.

Fig. 8 is a similar sectional view showing the operation of the frictional mechanisms at the hinged portion of the device.

Fig. 9 is an enlarged plan view of the hinged portion of the device in open position.

Fig. 10 is a section taken on line 10-10 of Fig. 4.

As shown on the drawings:

The collapsible tooth brush embraces an 85 outwardly tapering brush head 1, made of ivory, bone, celluloid or other suitable non-corrosive material, having a notch 2, formed on each side thereof. A number of bristle tufts 3, are secured in the usual manner, in 90 the inner face of the brush head, and integrally formed on the inner end of said brush head 1, is an outwardly tapering handle section 4, the side walls of which converge toward one another from the outer 95 surface of the handle section to the inner face thereof, as clearly shown in Figs. 7 and 8, to form a wedge cross-sectioned portion 5, in the handle section. As shown in Fig. 9, the wedge shaped portion 5, of the handle 100 section extends to within a short distance of the outer end of the handle section. The end of the handle section to the outside of the wedge portion thereof is pivotally or hingedly connected by means of a pivot pin or bolt 6, to a smoothly rounded cup shaped brush container or casing 7, made of ivory, bone, celluloid or other suitable material.

Said container is open at the top and at its inner end which is of reduced channel cross section and is provided with flexible integral clamping jaws 8, between which the end 5 of the handle section 4, is positioned to receive the pivot pin 6. The end portions of the clamping jaws 8, to the outside of the pivot pin 6, are tapered outwardly to permit the tapered handle section to fit between 10 said clamping jaws when the tooth brush is in open extended position for use. An aperture or opening 9, is provided in the bottom of the reduced channel portion of the brush container, to the outside of the pivot pin 6, to permit the tooth brush to be hung up when closed.

The outer or closed end of the container 7, is of increased depth and width to permit the brush head to be folded into closed position 20 to seat within the container with the reduced end of said brush head resting or bearing upon a seat or ledge 10, formed near the top of the inner surface of the closed end of the container. The ledge 10, limits 25 the inward movement of the brush head in the container, whereby the ends of the various bristle tufts are spaced from the inner surfaces of the container as clearly shown in Fig. 4.

30 When the tooth brush is closed, as shown in Figs. 3 and 4, the front or outer end of the brush head 1, contacts the inner surface of the closed end of the container, while the widest portion of the brush head contacts 35 the inner surfaces of the sides of the container, thus affording suitable ventilating or draining openings between the outer edge of the brush head and the inner walls of the container on each side of the widest portion 40 of the brush head. To permit the tooth brush to be readily opened into a position for use, and afford an additional ventilating means for the tooth brush, a recess 11, is formed or cut in the margin of each of the 45 side walls of the container 7, opposite one another in a position to register with the notches 2, of the brush head when the tooth brush is folded, so that the fingers of a person may engage through said recesses and 50 in said notches to frictionally draw the brush head outwardly to rotate on the pivot pin 6, into an open position. The depth of the recesses 11, is sufficient to afford ventilating

openings between the side of the casing 9, and the inner surface of the brush head 1, 55 when the device is closed as clearly shown in Fig. 10. Due to the wedge cross-sectioned portion 5, of the brush head, the flexible clamping sides or jaws 8, are frictionally sprung outwardly, as shown in Fig. 8, during the opening of the tooth brush, and spring back into normal position clamped against the sides of the wedge portion 5, 60 when the tooth brush is in open extended position for use as shown in Figs. 2 and 7.

I am aware that numerous details of construction may be varied through a wide range without departing from the principles of this invention, and I therefore do 70 not purpose limiting the patent granted otherwise than necessitated by the prior art.

I claim as my invention:—

1. In a folding tooth brush, the combination of a handle comprising an elongated hollow casing, tapered to form a contracted channeled extension at one end, a brush having a reduced shank pivoted in the channeled extension so as to fold down into the cup shaped casing, said shank having the lateral 80 walls angularly related and yieldingly engaged by the side walls of the channeled extension to lock the brush in the unfolded position.

2. In a folding tooth brush, the combination of a handle comprising an elongated hollow casing with a contracted channeled extension, a brush having a reduced shank pivoted to the side walls of the extension at a distance from the end of the extension so 90 that the bottom of the channeled extension serves as a stop to limit the unfolding pivoted movement of the brush, said shank being provided with angularly related side walls adapted to be yieldingly engaged by 95 the side walls of the channeled extension to hold the shank of the brush down against the bottom of the channeled extension in the unfolded position.

In testimony whereof I have hereunto subscribed my name in the presence of two subscribing witnesses:

CONVERSE W. LLOYD.
